UNITED STATES PATENT OFFICE.

FRANK BARNGROVER, OF NEWTON, IOWA.

BALANCED VALVE FOR STEAM-ENGINES.

No. 905,275.

Specification of Letters Patent.

Patented Dec. 1, 1908.

Application filed March 10, 1908. Serial No. 420,270.

To all whom it may concern:

Be it known that I, FRANK BARNGROVER, citizen of the United States, residing at Newton, in the county of Jasper and State 5 of Iowa, have invented certain new and useful Improvements in Balanced Valves for Steam-Engines, of which the following is a specification.

The present invention relates to slide 10 valves of that type which are commonly employed in connection with reciprocating steam engines, and has for its primary object to design a valve embodying a novel construction whereby the same is balanced 15 and is enabled to move back and forth upon its seat without the undue wear and tear incident to those valves in which an excessive pressure acts upon one side thereof.

The invention further contemplates a 20 valve which will be evenly balanced at every point in its movement and which can be readily mounted within the steam chest of an ordinary engine.

For a full description of the invention 25 and the merits thereof and also to acquire a knowledge of the details of construction and the means for effecting the result, reference is to be had to the following description and accompanying drawings, in which:

30 Figure 1 is a longitudinal sectional view through a balanced valve constructed in accordance with the invention. Fig. 2 is an end view of the same on a reduced scale. Fig. 3 is a plan view of the interior of the 35 cover. Fig. 4 is a bottom plan view of the valve proper.

Corresponding and like parts are referred to in the following description and indicated in all the views of the drawings by the 40 same reference characters.

Referring to the drawing, the numeral 1 designates the steam chest of an engine, and 2 the induction ports leading from the steam chest to opposite ends of the cylinder. A 45 valve seat 3 which is in the nature of a flat plate is applied to the upper face of the cylinder, a layer 4 of packing material being interposed between the members to form a tight joint and prevent any leakage of the 50 steam. As illustrated this valve seat 3 is shown as formed with a central port 5 communicating with the exhaust 6, and the end ports 7 communicating with the induction ports 2 of the cylinder. It will also be observed that the ports 5 and 7 are laterally 55

elongated and are arranged parallel to each other. Rigidly secured to the valve seat 3 is a cover 8 which has an arched formation and in the present instance is approximately semicircular in cross section. The interior 60 of the cover 8 is formed with a central channel 9 located directly opposite the exhaust port 5 of the valve seat, and end channels 10 located directly opposite the end ports 7 of the valve seat. It will be observed that 65 the ports 5 and 7 of the valve seat have a length slightly greater than the internal diameter of the cover 8, and that the ends of the channels 9 and 10 are flared outwardly as indicated at 11 and communicate with the 70 corresponding ports of the valve seat.

Slidably mounted upon the valve seat 3 is a valve comprising a stem 12 and the heads 13, the said valve being reciprocated back and forth upon its seat by means of a 75 valve rod 14 actuated in any suitable manner. Each of the heads 13 is formed with a flat face sliding upon the valve seat 3, and with a curved face corresponding to the interior of the cover 8. The curved face of each 80 of the valve heads or the portion of the valve heads adjacent the cover is grooved to receive a packing band 15. The base of these grooves is formed with a depression 16 which is enlarged at the upper portion of the head 85 to form a chamber 17 which faces directly away from the valve seat. It will also be observed that the end portions of the depressions 16 adjacent the flat face of the valve heads are offset as indicated at 18 so 90 as to be deflected toward the ends of the valve. It will further be observed that the opposite ends of the valve have the lower edges thereof beveled or cut away at 19 so that in the position of the valve shown in 95 Fig. 1 live steam from the valve chest will enter the induction port 2 at the left of the valve and from the induction port will pass through the depressions 16 into the chamber 17 and act against the inner face of the 100 packing band. It will also be evident that at this position of the valve the steam or other fluid pressure medium will enter the channel 10 at the left of the valve through the flared ends thereof so as to act upon the 105 exterior face of the packing band. The head 13 at the left of the valve will thereby be completely balanced so as to reciprocate upon its seat with the minimum amount of friction. The opposite end of the valve will 110

also be balanced since it will be observed that the exhaust steam from the induction port at the right hand end of the valve will be permitted to pass entirely around the 5 valve stem. It will thus be apparent that with the present improved construction of slide valve the fluid pressure medium will act upon all sides of the valve so as to balance the same at all positions thereof and 10 thereby permit the valve to operate without undue wear and tear.

Having thus described the invention, what is claimed as new is:

1. In a slide valve, the combination of a 15 valve seat, a valve cover applied to the valve seat and having a channel formed in its interior face, a valve mounted between the cover and valve seat, and a packing band carried by the valve, the valve being provided under the packing band with a depression and the fluid pressure medium being admitted both to the depression of the valve to act upon the inner face of the packing band and also to the channel of the cover 20 25 for acting upon the outer face of the packing band.

2. In a slide valve, the combination of a valve seat formed with ports, a cover applied to the valve seat and formed in the interior 30 face thereof with channels which communicate with the ports, a valve mounted between the valve seat and cover and formed with a groove, a depression being provided at the

base of the groove and the depression communicating with the port of the valve seat, 35 and a packing band arranged in the groove of the valve, the fluid pressure medium being admitted to the depression of the groove to act upon the inner face of the packing band and also to the channels of the cover for 40 acting upon the outer face of the packing band.

3. In a slide valve, the combination of a valve seat formed with ports, a cover applied to the valve seat and provided in its 45 interior with channels communicating with the ports of the valve seat, a valve mounted upon the valve seat and comprising grooved heads, depressions being formed at the base of the grooves, the depressions being adapted to communicate with the ports of the valve seat and being enlarged to form chambers which are disposed opposite to the valve seat, and packing bands arranged in the grooves of the valve, the fluid pressure 50 55 medium being admitted to the depressions in the groove to act upon the inner face of the packing bands and being also admitted to the channels of the cover to act upon the outer face of the packing bands.

In testimony whereof I affix my signature in presence of two witnesses.
